CONVERTIBLE, MULTIPLE CAPACITY, HOIST
CHAIN STRUCTURE

Fredrick W. Coffing, Danville, Ill.

Application November 21, 1941, Serial No. 419,870

4 Claims. (Cl. 254—188)

This invention relates to a chain hoist and more particularly to a convertible multiple capacity chain structure therefor.

The chief object of this invention is to provide a chain structure that is readily convertible from one capacity and speed to another and with a minimum of effort.

The chief feature of this invention consists in including in a load supporting chain structure, a chain, a load support and a readily operable connection whereby the latter when conditioned in one position, the hoist for one operation can elevate or lower a load at one speed and for the same operation when otherwise conditioned in another position can elevate or lower twice that load at half the previous speed.

Another chief feature of the invention resides more specifically in the snap-hook, its mounting and chain connection, whereby sufficient strength and clearance is provided.

Other objects and features of the invention will be set forth more fully hereinafter.

The full nature of the invention will be understood from the accompanying drawing and the following specification and claims:

In the drawing, Fig. 1 is a side elevation of a hoist, et cetera, embodying the invention, parts thereof being shown by full lines in the high speed half load condition, dotted lines of the same parts indicating the half speed full load condition.

Fig. 2 is a view at right angles to Fig. 1 of the sprocket pulley, snap-hook and anchorage portions of the invention.

Fig. 3 is a central sectional view through the snap-hook.

In the drawing, 10 indicates generally a hoist body of two pieces 10a and 10b and the same pivotally supports a hoist supporting hook 11. The hoist body mounts an operating and control handle 12—see Figs. 1 and 2—formed integral with the two-piece housing 10 and as extensions of the portions 10a and 10b thereof, are the projections 13a and 13b, respectively. Extending through the same are the apertures 14a and 14b, respectively.

Positioned in said apertures is the pivot member 15 having the head portion 15a and apertured at 15b for cotter key 16 reception. Positioned immediately adjacent each of the portions 13a and 13b are the links 17a and 17b, same being spaced apart by the projecting portions 13a and 13b. The free end of these links are connected by a similar pivot member 18 having the head portion 18a and the aperture 18b

at opposite ends, the latter receiving the cotter key 19. This provides a spaced portion on the member 18 between the two links 17a and 17b and this constitutes a hook anchorage and the resulting structure is a loop anchorage pivotally supported by the hoist housing 10.

A chain 20 is associated with and passes through the housings 10a and 10b in the usual manner, and one end thereof may be provided with a block portion, or the like, 21 to prevent complete withdrawal of the chain through the housing.

The other end of the chain 20 supports a hook structure—see Fig. 3. This hook structure 22—see Figs. 1 and 3—is provided with a hook-like end 23 providing a throat 23a between the face 23b and the opposed face 23c. The throat 23a is adapted to hook upon and partially embrace the member 18.

20. The body portion 22 of the hook is chambered as at 25 and therein is mounted a ball locking member 26 partially exposed to the throat 23a upon the face 23c. Said ball is normally constrained outwardly by means of spring 26a, the tension of which may be adjusted by the headless set screw 27. The body portion 22 is apertured as at 28 to receive the rivet 29 which unites the two spaced link members 30, a part of chain 20 and the end thereof.

30. There is provided a load support generally indicated by the numeral 31. It is formed of two pieces—see Figs. 1 and 2—which are suitably connected together and which pivotally support the retained portion of a load supporting hook 32.

35. These supporting structures 30 also have two parallel ears and in the space therebetween is positioned a sprocket gear 34—see Figs. 1 and 2—rotatably supported upon a shaft 35, or the like, extending through the ears. The root of the 40 groove or channel between the two ears indicated by the numeral 36, provides for a chain and hence, the teeth of the sprocket gear wheel 34 always mesh with the chain 20.

45. As illustrated by the full line showing in Fig. 1, the snap-hook structure 22 is engaged with the body portion 31, since the former locks therewith and the sprocket as shown in Fig. 1 when the last link is in the channel, and hence, the support structure 31 is connected to the hoist 50 by a single strand of chain. The operation of the hoist accordingly, will lift a load at a predetermined rate for a given operation of the handle 12 and a given load within the capacity of the load hook, chain, et cetera.

55. When it is desired to double the capacity of a

single chain, the snap-hook is removed from the load support engagement full-line position—see Fig. 1—and snapped upon the member 18—see dotted lines Fig. 1. In this position it will be apparent that the two strands of chain will be able to support double the previous load. However, since for the same given operation of the handle, each of the double strands move at the same rate, the result is that the rate of elevation or lowering of the load will be half that of the initial rate of raising or lowering the load when a single strand arrangement is utilized as previously described.

For the purpose of a complete understanding of this invention, reference is had to the following Coffing patents, which are representative of the type of hoist and hoist mechanism more particularly included within the housings 10a and 10b or mounted on the housings 10a and 10b. These patents are

While the invention has been illustrated and described in great detail in the drawing and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a chain hoist having a housing with a chain channel therethrough, a link, load supporting, chain passable through the channel, chain engaging and moving means in the hous-

ing, a load engaging hook responsive to chain movement, a channelled body means pivotally supporting the load engaging hook, and a chain engaging pulley in the channel, the chain bearing on the pulley for supporting and moving the body means, the combination of an anchor hook carried by one end of the chain and normally non-passable through the body means channel, a loop structure permanently and pivotally mounted on the housing between the entrance and outlet of the channel, the anchor hook having selective engagement with said loop structure for chain reeving purpose, and means carried by the anchor hook for detachably locking the loop structure and anchor hook together when in selected engagement.

2. Mechanism as defined by claim 1 characterized by the loop structure including a pair of spaced links, the housing pivot being interposed therebetween at one end, and the anchor hook engageable portion constituting the connection between the free and other ends of said links.

3. Mechanism as defined by claim 1 characterized by the detachable locking means including a locking portion normally constrained to locking position at all times.

4. Mechanism as defined by claim 1 characterized by the loop structure including a pair of spaced links, the housing pivot being interposed therebetween at one end, and the anchor hook engageable portion constituting the connection between the free and other ends of said links, said anchor hook having pivotal connection to the chain and a link free end connection receiving, angularly directed, notch, the mouth being between the pivotal connection and notch root, the locking means including a member exposed to the notch between the mouth and root thereof and yieldingly constrained for projection into the notch.

FREDRICK W. COFFING.
